ELECTRONIC COUNTING AND COMPUTING ARRANGEMENTS**John Reginald Acton, Beeston, Nottingham, England, assignor to Ericsson Telephones Limited****Application July 19, 1956, Serial No. 598,856****Claims priority, application Great Britain July 25, 1955****6 Claims. (Cl. 315—84.6)**

The present invention relates to electronic counting and computing arrangements, and particularly to such arrangements which include one or more gaseous discharge tubes each containing a plurality of electrode discharge points spaced a uniform distance apart in a ring around and equidistant from a common electrode.

It is an object of my invention to provide improved voltage stabilising arrangements for use, and in combination, with the aforesaid discharge tubes which are, for instance, described in United Kingdom patent application Number 1,324/49 (Serial Number 712,171). This patent application relates to a discharge tube having a plurality of cathode electrode discharge points disposed equidistantly from the discharge surface of a common anode electrode. In such a tube a discharge glow investing one of the cathode discharge points is caused to move to another cathode discharge point by way of two intermediate "guide" electrodes in response to each impulse applied to the circuit arrangement in which the tube is included. Circuit arrangements including such multi-electrode discharge tubes are also described in the aforesaid Patent Number 712,171, and in United Kingdom patent application Number 32,072/53.

The arrangements described in the above-mentioned British patents suffer from the drawback of sometimes failing to operate satisfactorily when a plurality of discharges is produced in the discharge tube. The potential of the anode of such tube is progressively reduced as the number of discharges present in the tube increases, thus rendering unstable the value of the applied potentials necessary, on the one hand, to produce further discharges in the tube, or, on the other hand, to cause the existing discharges to move from one cathode to another. The drawbacks of the known multi-electrode discharge tubes will be set forth in greater detail further below.

This present invention is in the nature of an improvement on the impulse counting arrangements depicted and described in the aforesaid patent application Number 32,072/53, and overcomes the aforesaid drawback by providing in these arrangements means whereby the potential at the anode of a discharge tube containing a plurality of cathodes is maintained automatically at a substantially constant voltage without regard to the number of discharges existing in the discharge tube and the corresponding variations in the load therein.

According to my invention I provide an arrangement for counting and storing electrical pulses comprising a gaseous electric discharge tube containing an anode and a plurality of cathodes, means for applying a pulse to a cathode in said discharge tube and storing it within the discharge tube in the form of a discharge between the anode and said cathode, means for applying a pulse to a plurality of cathodes in common and thereby causing a discharge to move from one cathode to another cathode, means whereby an impulse stored in the tube in the form of a discharge is counted out from said tube in pulse form, in combination with anode potential stabilizing means, whereby a potential derived from a direct current

2

source is applied to said anode of the discharge tube by means of a thermionic valve, and wherein a cathode follower circuit of said thermionic valve is connected to said anode and adapted to maintain automatically the value of the potential thereat within a determined range of values.

Again according to my invention I provide voltage stabilising arrangements for use with a variable load wherein a potential derived from a direct current source is applied to an anode of a thermionic valve, and a cathode of said valve is connected to a cathode follower circuit, and wherein a potential at the load is derived from said cathode of said valve and is maintained automatically at a value within a determined range of values without regard to the value of the load current.

The present invention will now be more fully described with reference to the accompanying drawing which shows a simple embodiment of my invention. In this simple circuit arrangement I provide a gaseous discharge tube

DTD in which the discharge points of thirty electrodes are spaced a uniform distance apart and arranged in a ring around the discharge surface of a circular anode A common to the said thirty electrodes. One or more auxiliary electrodes may also be provided and be situated 20 in suitable positions with respect to the main electrode assembly as described later. Each electrode in the tube DTD is provided with separate means of access from the containing bulb or envelope. Three half-wave rectifying valves DTA, DTB, and DTC, with a thermionic triode 25 valve DTE are also included in the depicted arrangement. For the purpose of this description, ten of the said thirty electrodes in tube DTD will be termed cathodes and designated T1 to T10, a further ten will be termed first 30 guide electrodes and designated GA1 to GA10, and the remaining ten will be termed second guide electrodes and designated GB1 to GB10. When so termed the said thirty electrodes, of which a part only are shown symbolically, 35 are arranged around anode A in the order cathode T1, first guide GA1, second guide GB1, cathode T2 and so on in the same order with second guide GB10 adjoining cathode T1.

In this embodiment of my invention the anode of valve DTE is connected to the positive pole of a source of suitable direct current by way of lead PA, and the negative 40 pole of the said direct current source is connected to a zero potential common lead Z. With anode A of discharge tube DTD connected to the cathode of valve DTE, and by way of resistor R11 to zero potential at lead Z, the said resistor R11 forms a "cathode follower." 45 Also connected by way of leads PA and Z to the described direct-current source, which we will term the main source of potential, and in parallel with valve DTE is a potential dividing arrangement consisting of resistors R13, R14 and R15, three half-wave rectifying valves 50 DTA, DTB and DTC, and a further resistor R16. Resistors R13 and R14 are provided with means whereby the potential at points x and y respectively may be varied for a purpose which will be described later. The voltage-tapping points x and y are also connected to the grid 55 electrode of valve DTE by means of unsymmetrical conductive elements MR1 and MR2 respectively. Tapping points x and y are also connected to the zero potential common lead Z by means of decoupling capacitors C4 and C5 which serve to ensure that only the steady direct 60 current potential developed at these tapping points is applied to the grid of valve DTE. Valves DTA, DTB and DTC with their associated resistor R16 form a reference voltage source.

Each cathode T1 to T10 in discharge tube DTD is connected by way of a separate resistor R40 to R49 respectively to zero potential at lead Z. Whilst each first 65 guide GA1 to GA10 and second guide GB1 to GB10 is

taken, by way of a resistor in the groups of resistors R30 to R39 and R20 to R29 respectively, to means whereby a suitable negative-going impulse may be applied sequentially to the said groups of first guides and second guides. In the simple circuit depicted on the accompanying drawing such means are formed by switches SW1 and SW2 which are connected to the commoned groups of resistors R30-R39 and R20-R29 respectively and to direct-current sources ND and NC.

The commoned group of resistors R40-R49 associated with the cathodes T, of tube DTD are connected to the grid of valve DTE by way of capacitor C1 and resistor R17, similarly resistor groups R30-R39 and R20-R29 are also connected to said grid by way of capacitor/resistor combinations C2/R18 and C3/R19 respectively. The capacitor in each such combination serves to prevent the main direct-current source from being short circuited by way of resistor R12.

When the pressure and content of the gaseous or other filling in the described tube and valves, the spacing of the electrodes therein, and the values of the described resistors, capacitors, and sources of potential are all suitable, a discharge is produced in tube DTD, and the glow thereof caused to invest cathode T1, when a pulse of suitable negative potential is applied to the said cathode T1. Such a pulse may conveniently be derived by the brief application of the potential at terminal E to the point marked w. Such a discharge between anode A and cathode T1 is caused to move, and to invest cathode T2, when a pulse of suitable negative potential is applied sequentially to the first guides GA and second guides GB in that order. The discharge glow is caused to move to and invest cathode T10 however when the said sequential negative going pulses are applied to second guides GB and first guides GA in that order. Each such pair of sequential voltage impulses may be derived from a single voltage pulse of suitable characteristics modified in known manner, or as in the simple arrangement shown on the accompanying drawing in which the sequential operation of switches SW1 and SW2 in that order cause a negative going pulse derived from direct current sources ND and NC to be applied to the described groups of first guides GA and second guides GB.

The production of such a single discharge in tube DTD causes current of a particular value to flow through the tube DTD. This current is drawn from the main direct-current source, and its value remains substantially constant regardless of the position of the discharge in the tube DTD. When however such a discharge has been caused to move in the manner described from cathode T1, and its glow invests, for example, cathode T4, the production of a second discharge in the tube in a similar manner will cause the current flowing through the tube to rise, and at the same time will tend to lower the value of the positive potential at anode A of the tube DTD. Each additional discharge produced in the tube DTD will have a similar effect and will tend to lower progressively the potential at anode A. Such changes to the value of the said potential are undesirable as they render unstable the value of the potentials which it is necessary to apply to the first and second guides GA and GB in order to move the discharges in the tube DTD from the cathodes T on which they are halted to other cathodes T. Thus it is desirable to maintain the potential at anode A of the tube DTD in the region of a particular value regardless of the number of discharges existing in the tube DTD, or of the positions of the electrodes invested by the discharge glows. Such a value of potential will be termed the optimum value.

In this present invention the potential at the anode of the multi-cathode discharge tube DTD is maintained by means of a thermionic triode DTE in the region of an optimum value at all times that the tube contains one or more discharges. Triode DTE is arranged in a characteristic relationship to potentials derived from a main

source of direct current, to the electrodes of the multi-cathode discharge tube DTD, and to a potential dividing arrangement formed by asymmetrical elements MR1 and MR2 and resistors R13, R14, and R15 which is connected to valves DTA, DTB and DTC, which with resistor R16 form a reference voltage source. In the described arrangement of my invention the production of a discharge in tube DTD and the resultant flow of current through triode DTE causes a potential to be developed across resistor R11, and the positive potential at the electrode connected end of resistor R11 reaches a particular value. The production of an additional discharge in tube DTD in the manner described previously, which tends to reduce the value of the positive potential at the said anode A of tube DTD, also tends to lower the value of the positive potential at the cathode of triode DTE and at the adjoining end of resistor R11. Such a tendency increases the potential difference between the cathode and grid electrodes of triode DTE, and causes the current flowing through triode DTE to increase, and in consequence the potential difference across the cathode follower resistor R11 returns to a value in the region of its previous value. In this way the tendency towards a lower positive potentials at the anode of tube DTD is reversed, and by choice of suitable components in the form of triode DTE and resistor R11 the potential at anode A is restored to a value which is equal, or substantially equal, to its previous value. This value may conveniently form the optimum value of positive potential at which it is desirable to maintain the anode A of tube DTD. Such a value of potential is determined by the potential difference across resistor R11, and is dependent upon the value of the current flowing in triode DTE. The value of the current in triode DTE is itself dependent upon the value of the potentials at its anode, cathode and grid electrodes. The potential at the anode of triode DTE is fixed as it is connected directly to the positive pole of the main direct-current source by way of lead PA. The grid electrode of triode DTE is held at a potential determined by the value of the positive potential derived from the main current source by way of resistor R12, and the potential derived from the reference voltage source formed by valves DTA, DTB and DTC and resistor R16, in association with the potential dividing arrangement of resistors R13, R14, R15. The potential at the cathode of valve DTE is determined by the value of resistor R11, and a resistor of 100,000 ohms provides a satisfactory value of potential.

In one arrangement of the invention which has been found to be satisfactory the potential derived from the main current source is of the order of 400 volts, whilst the voltage of direct-current sources, NA, NC and ND is each of the order of 60 volts. The characteristics of triode DTE are such that it functions satisfactorily when the positive potential at the grid electrode is of the order of 250 volts, and the positive potential at points x and y is of the order of 260 volts and 240 volts respectively. With such an arrangement should the value of the positive potential at the grid of triode DTE tend to rise above the potential at point x current will flow through element MR1 and resistors R13, R14 and R15, and cause the value of the potential at the grid electrode to fall to the value of the potential at point x. Similarly should the value of the potential at the grid of triode DTE tend to fall below that at point y current will flow through element MR2 and resistors R16, R13 and R14, and cause the potential at the grid of triode DTE to rise to the value of the potential at point y.

When a discharge has been produced in tube DTD and a discharge glow has been caused to invest cathode T1 in the manner described, the subsequent application of a pair of suitable negative going pulses of potential sequentially to the first guides GA and second guides GB, in that order, will have the effect of moving the said discharge from cathode T1 to cathode T2 in the

following manner. On the closure of switch SW1 the negative potential derived from direct-current source NC is applied to resistors R30 to R39 and thence to first guides GA1 to GA10, at the same time it is also applied to capacitor C2 and causes a negative-going pulse of potential to be applied to the grid electrode of triode DTE by way of resistors R18 and R17. The application of this first negative-going pulse of the said pair of pulses to the grid of triode DTE causes a reduction in the value of the current through the said triode DTE with a consequent reduction in the value of the positive potential at the anode of tube DTD. At the same time the value of the potential at first guides GA is made considerably more negative. Thus conditions are produced in which the potential difference between the anode A and cathode T1 in tube DTD is reduced simultaneously with an increase in the potential difference between the said anode A and first guides GA1 to GA10, and the potential difference between anode A and first guide GA1 becomes so much greater than the potential difference between the anode A and the adjoining cathode T1 that the discharge ceases to invest cathode T1, and moves to and invests first guide GA1.

The second pulse of the pair of negative-going pulses is applied, by the closure of switch SW2, to second guides GB1 to GB10 by way of resistors R20 to R29, and to the grid of triode DTE by way of capacitor C3 and resistor R19. The second pulse is more negative than the first pulse as it is derived from direct-current sources ND and NC in series, and the negative-going pulse at the grid of triode DTE causes a further reduction in the current through the said triode DTE, and a consequent lowering of the value of the positive potential at the anode of tube DTD. With second-guide GB1 at a considerably more negative potential than the potential at guide GA1 conditions for the movement of the discharge again prevail, and the discharge moves to and invests second guide GB1. The reduction in the value of the current through triode DTE, which occurs with the receipt of a pair of negative-going pulses of potential at the grid of the said triode, is such as to cause the value of the positive potential at the anode A of the tube DTD to fall below the described optimum value, and following such pulses the described triode valve current and tube anode potential are restored to their pre-pulsed values in the following manner. The application of the negative-going pulses to the grid of triode DTE reduces the positive potential at the said grid to a value below that of the positive potential at point y, and current flows through asymmetrical conducting element MR2 and causes the positive potential at the said grid to rise to a value in the region of the potential at point y. This increased positive potential at the grid of triode DTE causes the current through the valve to increase and to return to its pre-pulsed value.

The cessation of the pair of pulses by the opening of switches SW1 and SW2 in that order, and the concurrent increase in the value of the positive potential at the anode A of tube DTD, produces conditions in which, when the value of the negative potential at second guide GB1 falls below the value necessary to maintain a discharge, the potential difference between anode A and the adjoining cathode T2 has been restored to such a value that the discharge investing second-guide GB1 is caused to move to and invest cathode T2. In this way the application of a pair of negative-going pulses of potential in sequence to the commoned groups of guide electrodes GA and GB causes the discharge to move from one cathode T to the next immediately adjacent cathode T. At the conclusion of such a movement the potential at the anode A of tube DTD is restored to a value in the region of the optimum value in the manner described.

With the said discharge investing cathode T2 a second discharge may be produced in tube DTD and caused

to invest cathode T1 in a similar manner to that described with reference to the first discharge. Such an additional discharge causes the current through tube DTD to increase, and in consequence the value of the positive potential at the anode A of the said tube tends to fall. This tendency towards a lower value of positive potential at tube DTD is communicated to the cathode of triode DTE, and causes the current through the said triode to increase until the value of the positive potential at the anode of tube DTD and the adjoining end of resistor R11 is restored to a value in the region of the optimum value.

When two discharges have been produced in the tube DTD each operation of switches SW1 and SW2 as described will cause a pair of negative-going pulses to be applied in sequence to the commoned first guides GA and commoned second guides GB and the discharges will move concurrently to, and invest, the next immediately adjacent cathode T. During each such cycle of movement the potential at the anode A of tube DTD is varied in the manner described to facilitate the movement of the discharges but on completion of each cycle of movements the positive potential at the said anode A is restored to a value in the region of the optimum value. Each additional discharge produced in tube DTD will cause the value of the current through the said tube to rise, and the value of the positive potential at the anode of the tube will tend to fall with each such increase of current but will be held at a value in the region of the optimum value by the automatic voltage stabilizing effect of the potential dividing arrangement in association with triode DTE and its cathode follower circuit arrangement. With such an arrangement should the value of the positive potential at the grid electrode of triode DTE rise above the predetermined value of potential at point x current will flow by way of asymmetrical conducting element MR1 and the potential at the triode grid will be held at the potential value at point x.

The described arrangements for guiding a discharge in tube DTD from one cathode T to the next immediately adjacent cathode T are equally suitable for use when a single discharge exists in the tube or when the maximum number of such discharges have been produced therein. With such discharge guiding arrangements the direction in which the discharge is guided around a ring of cathode and guide electrodes may be reversed by reversing the connections from switches SW1 and SW2 to the commoned first guides GA and resistors R30 to R39, and the commoned second guides GB and resistors R20 to R29.

In order to maintain the potential points x and y at a constant value regardless of variations in the potential derived from the main source of direct current the potential dividing resistors R13, R14 and R15 are arranged in parallel with three half wave rectifying diodes DTA, DTB and DTC as shown which with resistor R16 form a suitable source of reference voltage.

The arrangement by which the potential at anode A of tube DTD is maintained in the region of a predetermined value when a number of discharges in the tube is increased to a maximum is also satisfactory when a number of discharges in the tube is reduced to a minimum. Any reduction in the number of discharges in tube DTD automatically reduces the value of the current through the tube, and in consequence the value of the positive potential at anode A tends to rise, this "voltage rising" tendency is communicated to the cathode of triode valve DTE, and causes a reduction in the value of the current through triode DTE which reduction continues until the potential at anode A of tube DTD, at the cathode of triode DTE, and at the adjoining end of the cathode follower resistor R11 is stabilised at a value in the region of the described optimum. With such an arrangement the investment of any cathode T

may be used to develop a potential across a resistor connected thereto, and such a potential may be applied to an output lead and form an outgoing pulse of potential. Such a resistor R2 and outgoing pulse lead OP are shown connected to cathode T1. In this way a plurality of discharges produced in a tube DTD, in consequence of the receipt of a like number of pulses, may cause a like number of impulses to be "counted out," thus the arrangement may be regarded as a means of storing impulses.

An alternative means of producing a discharge in the multi-cathode tube DTD between anode A and a predetermined cathode T is provided in the invention by including switching means which are not shown on the drawing for disconnecting the positive potential applied to anode A, and providing at least one auxiliary electrode in the tube DTD. In one such arrangement the discharge point of an auxiliary electrode ST is situated in close proximity to the discharge point of the selected cathode T1, and the electrode ST is connected by way of switch SW3, terminal E, and resistor R1 to the negative pole of a source of direct-current NA. The gap between the discharge points of electrode ST and cathode T, and the potential derived from direct-current source NA are such that with switch SW3 closed a minute discharge is produced between the said electrodes. Electrode ST thus acts as a so-called "keep-alight" electrode and maintains the space around the discharge point of cathode T1 in an ionised condition. In the absence of a potential from anode A and with the associated switching means open, no discharge exists between anode A and cathode T. When the said switching means are closed a positive potential is applied to anode A, the ionised space around cathode T1 facilitates the production of a discharge between the said anode A and cathode T1, and a discharge glow invests the said cathode T1. In a variation of such discharge producing means which is not shown on the accompanying drawing, two auxiliary electrodes are provided in the multi-cathode tube and are connected by switching means to a suitable source of direct current. The auxiliary electrode discharge points are arranged to form a small discharge gap in a position adjoining a predetermined cathode T. In the absence of a discharge between the auxiliary electrodes the potential difference between the anode and the predetermined cathode T is insufficient to produce a discharge. When a discharge is produced between the auxiliary electrodes on the closure of the switching means the space around the predetermined cathode T becomes ionised, and under such conditions a discharge is provided between the anode and the said cathode T.

Although the voltage stabilising arrangement has been described with reference to a single discharge tube containing a plurality of discharge paths, its use is not confined to such tubes, and its application to many other forms of variable load will be obvious after this simple application of my invention has been understood.

What I claim is:

1. In an arrangement for counting and storing electrical pulses, comprising a gaseous electric discharge tube containing an anode and a plurality of cathodes, a direct-current source, the positive potential of which is applied to said anode, means for applying at least one pulse to one of said cathodes and storing the pulse within the discharge tube in the form of a discharge between said anode and said last named cathode, and means for applying a varying number of pulses to a varying number of said cathodes in common and thereby causing a varying number of discharges to move from one group of said cathodes to another group of said cathodes, thereby varying the load in said discharge tube; the improvement of stabilizing means for maintaining automatically

the value of the potential at said anode of said discharge tube stable within a determined range of values regardless of changes in the number of discharges in said discharge tube.

5. 2. In an arrangement for counting and storing electrical pulses, comprising a gaseous electric discharge tube containing an anode and a plurality of cathodes, a direct-current source, the positive potential of which is applied to said anode, means for applying at least one pulse to one of said cathodes and storing the pulse within the discharge tube in the form of a discharge between said anode and said last named cathode, and means for applying a varying number of pulses to a varying number of said cathodes in common and thereby causing a varying number of discharges to move from one group of said cathodes to another group of said cathodes, thereby varying the load in said discharge tube; the improvement of stabilizing means for maintaining automatically the value of the potential at said anode of said discharge tube stable within a determined range of values regardless of changes in the number of discharges in said discharge tube, said stabilizing means comprising a thermionic valve having anode means, cathode means and grid means therein, a cathode follower circuit associated with said thermionic valve and a reference voltage source connected in parallel with said thermionic valve to said direct current source, said anode means of said thermionic valve being connected to the positive potential of said direct-current source, said cathode means being connected to said anode of said discharge tube as well as to said cathode follower circuit, and said grid means being connected to said reference voltage source.
10. 3. In an arrangement for counting and storing electrical pulses, the improvement described in claim 2 in which potentials derived from said reference voltage source are applied by way of unsymmetrical conductive elements to said grid means of said thermionic valve and are adapted to maintain automatically the potential at said grid means within a determined range of values.
15. 4. In an arrangement for counting and storing electrical pulses, the improvement described in claim 2, in which said reference voltage source includes a plurality of diodes in series and a voltage divider in parallel with said diodes.
20. 5. Voltage stabilizing arrangements according to claim 2 wherein said grid means of said thermionic valve is coupled to said reference voltage source by at least two unsymmetrical conductive elements whereby a potential applied to said grid means is maintained automatically at a value within a determined range of values.
25. 6. In an arrangement for counting and storing electrical pulses, comprising a gaseous electric discharge tube containing an anode and a plurality of cathodes, a direct-current source, the positive potential of which is applied to said anode, means for applying at least one pulse to one of said cathodes and storing the pulse within the discharge tube in the form of a discharge between said anode and last last named cathode, means whereby a pulse stored in said discharge tube in the form of a discharge is counted out from said tube in pulse form, and means for applying a varying number of pulses to a varying number of said cathodes in common and thereby causing a varying number of discharges to move from one group of said cathodes to another group of said cathodes, thereby varying the load in said discharge tube; the improvement of stabilizing means for maintaining automatically the value of the potential at said anode of said discharge tube stable within a determined range of values regardless of changes in the number of discharges in said discharge tube, said stabilizing means comprising a thermionic valve having anode means, cathode means and grid means therein, a cathode
30. 7. 8.

follower circuit associated with said thermionic valve and a reference voltage source connected in parallel with said thermionic valve to said direct current source, said anode means of said thermionic valve being connected to the positive potential of said direct-current source, said cathode means being connected to said anode of said discharge tube as well as to said cathode follower circuit, and said grid means being connected to said reference voltage source. 5
